UNITED STATES PATENT OFFICE.

BARTHOLOMEW J. O'BRIAN AND GEORGE E. FUNK, OF KANSAS CITY, MISSOURI.

PROCESS OF MANUFACTURING CURVED ELECTROTYPE PLATES.

Application filed April 20, 1928. Serial No. 271,471.

This invention relates to a process of manufacturing curved electrotype plates to be used on rotary type presses, and has for its principal object the reproduction of any engraved or moulded surface, wood cuts, or pages of composite type in a flat surface to a cylindrical form suitable for use on a rotary press, without distortion.

The method now used in making curved electrotype plates is to mould by pressure, the subject that is to be reproduced in lead while in a flat shape, backing up said lead mould with some suitable reenforcing metal to prevent distortion, then depositing on the surface of the mould by electrolysis, a thin layer of metal, such as copper, to form a shell on which is reproduced the characters to be printed. This thin shell is removed from the mould and backed up with type metal to which it is secured by some suitable soldering material. The shell, with its backing is now in a flat shape, and must be curved to fit the printing drum of the press. In the process of curving this plate, the printing surface is distorted, due to the fact that the plate is quite thick (from three-sixteenths to one-half inch thick, depending on the type of printing press on which it is to be used), and the outer surface will be stretched, while the inner portion is compressed. This distortion is very noticeable when color printing is to be done, and more than one printing operation is required. The distortion of the different color plates is not the same, and it is impossible to get a proper register of the colors.

The purpose of the present invention is to overcome the distortion of the plate, and thereby produce an electrotype plate that will be an exact reproduction of the original surface.

A further purpose of the present invention is to make a curved electrotype plate by depositing by electrolysis on a mould having the reverse contour of the finished curved electrotype plate, a thin layer of metal.

A still further object of the present invention is to make a thin lead mould of an engraved or moulded flat surface, then curving said thin plate to the exact form of the finished curved electrotype plate, said mould then being used to produce a shell of metal by electrolysis.

With these general objects in view, as well as minor objects which will appear during the course of the detailed specification, ref-

erence will now be made to the accompanying drawings, which are submitted to more clearly set forth the different steps, in the manufacture of the present curved electrotype plate, in which

Figure 1, is a perspective view of a lead mould, formed by pressing said lead against a moulded or engraved flat surface.

Fig. 2, is a perspective view of said mould, shown formed to a curved shape in a curved block.

Fig. 3, is an enlarged cross-section taken on line III—III of Fig. 1.

Fig. 4, is an enlarged cross-section taken on line IV—IV of Fig. 2.

Fig. 5, is a perspective view of a curved mould with the reenforcing metal in position.

Fig. 6, is a perspective view of said mould with the shell formed by electrolysis thereon.

Fig. 7, is a perspective view of the printing side of the shell, removed from the mould.

Fig. 8, is a cross-section of the shell positioned in a casting box with the metal backing in position, and

Fig. 9, is a perspective view of the shell with the reenforcing metal secured to the back thereof.

Like reference characters designate like parts throughout the several views, and the numeral 10 designates a lead mould in which has been reproduced the characters from a flat surface. These characters are usually produced by placing the thin sheet of lead on the surface to be reproduced, and then applying hydraulic pressure to the outer surface of said lead sheet, to form an impression 11, of said characters therein. The thickness of this lead sheet is preferably about .010" thickness, while the depth of the impression made by the characters to be printed is substantially .005", thus making the inner surface 12 of the impressions formed in the lead sheet substantially on the central plane of said sheet. This is a very important requirement in the manufacture of the plate, because of the fact that the bottom surface of said depressions is the surface on which the printing surface of the electrotype plate is to be deposited, and due to the fact that these bottom surfaces are on the central plane of the lead sheet, there will be no stretching or compressing of the metal to distort the printing face. There

will be a compression of the face 13, and a

stretching of the surface 14, while the metal on the center plane will be neutral. This is a well established principal in the forming of metals.

5 As shown in Fig. 4, the lead mould 10, which is easily formed to shape, is pressed into a curved block 15, by any suitable means, and due to the softness of the metal will readily adapt itself to the exact contour 10 of said block. The curved side 16 of the block 15 is made of such a degree, that when the lead mould is positioned therein, the curvature of the bottom portion of the impression in said lead mould will be the same 15 as required by the printing surface of the electrotype plate.

In Figs. 3 and 4, it will be noted that a broken line C—L has been drawn which indicates the central plane of the mould sheet.

20 It is not desired to limit the mould to lead, as it may be made of wax, papier-mâché, or any other moulding material, suitable for the purpose.

The curved mould is now removed from 25 the block 15, and backed up with a suitable reenforcing metal 17, as shown in Fig. 5. This backing is secured to the lead plate by any suitable means, and serves to prevent distortion of the same during the process of 30 depositing a shell thereon. A deposit of copper is now made on the lead mould by electrolysis in the ordinary well known manner, to form a shell 18, having a printing surface 19. When it is desired to use the 35 plate for printing a very large number of sheets, a thin deposit of nickel may first be made, and then a thicker deposit of copper, thus giving the printing surface a harder texture to prevent wear. The shell is now 40 removed from the mould by inserting a sharp instrument between said shell and mould at one corner, and then pulling on the shell, thereby peeling the same from the mould while in the curved shape. The shell is now 45 placed in a mould 20, as shown in Fig. 8, and is backed up with a type metal 21, which adheres to the concave side of said shell, due to the application of soldering flux 22, such as tin. The thickness of the 50 backing of type metal is usually from three-sixteenths to one-half inch, depending on the type of press on which the electrotype plate is to be used. Due to the fact that it is difficult to cast a type metal backing of an exact thickness, the backing is usually 55 cast thicker than necessary, and then turned down to the proper thickness, thereby giving the printing surface a more accurate adjustment on the printing roll.

60 It will be noted that in this process, the printing surface of the electrotype plate has not been distorted by bending from the original surface from which it was produced, as described above, while in the ordinary process now in use, the printing surface of

the electrotype plate is greatly distorted, due to the fact that the shell is backed while in the flat condition, and then bent to the curved position.

Should it be attempted to deposit the shell 70 in a flat shape and then form the flat shell into the curved shape, before the backing is attached thereto, it will be found that due to the hardness of this shell, the contour of the shell will become irregular and not 75 of uniform curve. Due to the hardness of the metal and the different thicknesses of the metal, some portions of the shell will be curved, while others will be substantially flat, thus making it impossible to obtain 80 the desired printing surface.

With this process, it is very evident that several plates may be made for color work, which will properly register and produce the same result as is now produced on the flat 85 printing press.

We do not limit this invention to the process described and shown, as many modifications may be made within the scope of the appended claims without departing from 90 the spirit thereof.

What we claim as new and desire to be secured by Letters Patent is:

1. A process of manufacturing a curved electrotype plate consisting in depositing on 95 a curved mould a thin layer of metal to form a shell, then separating said shell from the mould, and backing up said shell with a re-enforcing metal.

2. A process of manufacturing a curved 100 electrotype plate consisting in depositing on a curved mould by electrolysis a shell of metal, separating said shell from the mould and backing it up with a reenforcing metal while in the curved shape. 105

3. The process of manufacturing curved 110 electrotype plates consisting in forming a mould to the shape that the finished plate is to be, then depositing by electrolysis a coating of metal to form a shell having a printing surface on its convex side. 115

4. The process of manufacturing a curved 120 electrotype plate consisting in forming a mould to the curve that the finished plate is to be, backing up said mould with a reenforcing metal, then depositing on said mould by electrolysis a coat of metal to form a shell having a printing surface on its convex side, then backing up said shell with reenforcing metal.

5. The process of manufacturing curved 125 electrotype plates consisting in forming an impression of characters in a thin, flat, soft metal sheet to a depth substantially one half the thickness of said metal sheet, then curving said metal sheet, then depositing by electrolysis on said curved metal sheet a shell of metal having a printing surface on its convex side.

6. The process of manufacturing curved 130

- electrotype plates consisting in forming an impression of characters in a thin, flat, lead sheet to a depth substantially one half the thickness of said lead sheet, curving said 5 moulded lead sheet, then backing it with a reenforcing metal, then depositing a thin sheet of metal on said moulded lead sheet to form a shell having a printing surface on its convex side.
10. 7. The process of manufacturing curved electrotype plates, consisting in forming a curved mould, depositing thereon by electrolysis a thin shell of metal, removing said shell from said mould and reenforcing the 15 back thereof with metal.
8. The process of manufacturing curved

electrotype plates consisting in making an impression in a thin sheet of lead of some moulded or engraved flat surface, forming said lead sheet into a curved shape with the 20 impressions on its concave side, backing up the convex side of said lead sheet with a reenforcing metal, depositing a thin coat of copper on said lead sheet by electrolysis to form a curved shell having a printing surface on its convex side and then backing up said plate with type metal.

In witness whereof, we hereunto affix our signatures.

BARTHOLOMEW J. O'BRIAN.
GEORGE E. FUNK.
